UNITED STATES PATENT OFFICE.

ABRAM C. MOTT, JR., OF PHILADELPHIA, PENNSYLVANIA, ASSIGNOR TO ABRAM COX STOVE COMPANY, OF PHILADELPHIA, PENNSYLVANIA, A CORPORATION OF PENNSYLVANIA.

COMBINED COAL AND GAS RANGE.

1,253,707.

Specification of Letters Patent. Patented Jan. 15, 1918.

Application filed May 26, 1916. Serial No. 100,038.

To all whom it may concern:

Be it known that I, ABRAM C. MOTT, Jr., a citizen of the United States, residing in Philadelphia, Pennsylvania, have invented 5 certain Improvements in Combined Coal and Gas Ranges, of which the following is a specification.

One object of my invention is to construct 10 a combined gas and coal range so that a single operating lever will control all of the dampers in order that the oven of the range may be used with either section of the range.

A further object of the invention is to 15 provide means for operating the several dampers and to arrange said means so as to act as a guard for the gas valves to prevent them being turned when the dampers are shifted in position for the range to be 20 used as a coal burning range.

A still further object of the invention is to provide a plate in the bottom of the range which acts as a closure for the opening in the bottom of the range when the 25 range is being used as a coal range, the plate acting as a deflector for the flame from the burners when the range is used as a gas burning range.

In the accompanying drawings:—

30 Figure 1, is a front view of the range illustrating my invention, showing the mechanism shifted so that the range can be used as a gas range;

Fig. 2, is a view similar to Fig. 1, with 35 the mechanism shifted so that it can be used as a coal burning range, the operating lever being shifted so as to prevent manipulation of the gas valves;

Fig. 3, is a vertical sectional view through 40 the oven of the range with the parts in the position illustrated in Fig. 1;

Fig. 4, is a sectional view through the oven of the range with the parts in the position illustrated in Fig. 2;

Fig. 5, is an end view of the range; and

Fig. 6, is a detached perspective view illustrating the deflecting plate and its operating mechanism.

Referring to the drawings, 1 is the body 50 of the range, which is of the ordinary type.

2 is the fire pot. 3 is the grate. 4 is the ash pit under the grate. 5 is the oven. 6

is the top plate of the range having the usual openings therein. 7 is the flue between the top of the range and the top 55 plate of the oven. 8 is the side flue and 9 is the bottom flue leading to the back flue 10 which communicates with the chimney. 11 is a pivoted damper forming communication with the upper flue 7 and the back flue 60 10 when it is desired to have a direct draft from the fire pot to the stack without passing around the oven when the range is used as a gas range so as to carry off the waste 65 gases which pass through the oven.

In the bottom plate is an opening 12 and directly under this opening are the two gas burners 13, in the present instance, and a pilot burner 14. At the front of the range 70 is the gas supply pipe 15 having handled 70 gas valves 16 for the two burners and for the pilot burner, as clearly shown in Figs. 1 and 2.

17 is a heavy metal plate which, when in the raised position as in Fig. 3, acts as a 75 deflecting plate for the flames issuing from the burners and, when in the position illustrated in Fig. 4, it acts as a closure for the opening 12 so that the products of combustion from the coal passing around the 80 oven from the fire pot will not escape under the bottom of the range but will pass to the back of the flue 10. The plate 17 may be lined with any suitable heat non-conductor if desired.

At each side of the oven are passages 18 through which the gases pass from the lower flue 9 into the oven when the range is burning gas, and in the upper portion of the oven are openings 19 which communicate 90 with a damper box 20 in which there is a pivoted damper 21 which is opened when gas is used, so as to carry off any waste 95 products of combustion from the oven to the back flue 10 as the damper 11 is also open.

22, 22 are dampers which are arranged to close the communication between the side flues 18 and the lower flue 9 when coal is used. 23 is another damper closing the communication between the side flue 8 and the 100 lower flue 9 when gas is used, so that all of the products of combustion from the gas burner will pass into and through the oven.

The deflecting plate 17 is pivotally mount-

ed on two crank shafts 24, 24^a, shown in Fig. 6, and these shafts have their bearings in the frame of the range. One of these shafts extends beyond the burner valves 16 and attached thereto is the operating lever 25, Figs. 1 and 2. This operating lever is of such a length that when turned to the position illustrated in Fig. 2, it will be located in front of the three burner valves 16 and will prevent them being turned while the lever is in its lowest position, but when the lever is turned back to the position illustrated in Fig. 1, the burner valves are exposed and can be turned. The cranks of the shafts are so proportioned that when the plate is elevated, as in Fig. 3, it is in the proper position to deflect the flame from the burners and when in the lower position, as in Fig. 4, it will close the opening 12 in the bottom plate.

One of the dampers 22 is mounted on the same shaft 26 as the damper 23 and this shaft 26 has an arm 27 and the other damper 22 has an arm 28 and these two arms are connected by a rod 29. Both the arms and the rod are on the outside of the range. The rod 29 extends to the side of the range and is attached to an arm 30 of a bell crank lever 31 adapted to a bracket on the range, and the arm 27 is connected by a rod 32 to the crank shaft 24^a, so that when the operating lever 25 is turned it shifts the dampers 22 and 23, as well as the plate 17.

In order to operate the pivoted dampers 21 and 11 at the upper part of the range with the plate and the other dampers, I connect a rod 33 with the other arm 34 of the bell crank lever and this rod is connected, in turn, to an arm 35 attached to the pivot of the damper 21, which extends through the side plate. The upper end of the rod 33 has a lug arranged to strike an arm 36 attached to a crank on the pivot rod 37 of the damper 11 and this arm 36 is notched to engage a detent 38 projecting from the side of the range and which retains the damper 11 in the position to which it is adjusted.

It will be seen that by the above construction, when the operating lever is in the position illustrated in Fig. 1, the parts are shifted so that the range can be used as a gas range, the lever being clear of the burner valves so they can be turned to allow the gas to flow to the burner. The plate 17 is in the elevated position so that it will act as a deflector. The dampers 22 are raised so as to allow the products of combustion to enter the oven, and the damper 21 and the damper 11 at the upper part of the range are both shifted to the open position to allow the products of combustion to escape from the oven to the stack, the damper 23 being in the closed position so as to prevent the products of combustion escaping through the flue 8 and around the oven.

When the operating lever is turned to the position illustrated in Fig. 2, it is in front of the burner valves 16 so that they cannot be turned, and the plate 17 is in its lowest position, closing the bottom plate of the range. The dampers 22 are closed so as to prevent any product of combustion passing into the oven, as is also the damper 21. The damper 23 in the side flue 8 is open. The damper 11 can be either opened or closed, as desired, since it is independent of the other dampers. When the parts are in this position, coal can be used and the products of combustion can pass directly to the back flue 10 when the damper 11 is opened, and when the damper 11 is closed the products of combustion will pass through the flues 7, 8, and 9, around the oven and to the stack 10.

I claim:

1. The combination in a combined gas and coal range, of an oven; a fire pot for coal; flues extending around the oven and communicating with the fire pot; a gas burner under the bottom plate of the range, said bottom plate having an opening therein; a movable deflector plate arranged to close the opening or to act as a deflector above the opening side flues leading from the lower flue to openings in the sides of the oven; dampers interposed between the lower flue and the side flue; an operating lever for engaging both the deflector plate and the dampers; a gas-supply pipe communicating with the burners; valves therein, the operating lever being so located that when the parts are moved to the position so that coal can be used the lever is in front of the gas valves, preventing their use.

2. The combination in a combined gas and coal range, of an oven; a fire pot; flues extending around the oven from the fire pot; a back flue with which the under flue communicates; a passage between the upper flue and the back flue; a damper for closing said passage; the upper part of the oven having openings therein; a damper arranged to close said openings; a passage at each side of the oven; a damper for closing said passages; a damper in the down flue; the bottom of the range having an opening therein; gas burners under the range in line with the opening; a deflector plate arranged to close the opening or to be elevated to act as a deflecting plate for the flames issuing from the burners; a single operating valve; and means connecting the plate and all of the dampers with the operating lever so that, when the operating lever is turned in one position, the plate and dampers are set so that gas can be used, and, when the lever is turned in another position, the plate and dampers are set so that coal can be used.

3. The combination in a combined gas and coal range, of an oven; a fire pot; flues extending around the oven from the fire pot;

a back flue communicating with the bottom flue; a pivoted deflecting plate mounted in the bottom flue; the bottom of the range having an opening therein directly under 5 the plate; burners under the bottom plate in line with the opening; cranks connected to the deflecting plate; an operating lever

connected to one of said cranks and arranged to raise or lower the deflecting plate; and valves for the burners so located as to be 10 at the back of the operating lever when the plate is in its lowest position.

ABRAM C. MOTT, Jr.
